UNITED STATES PATENT OFFICE.

WILSON WORTH BURSON, OF ROCKFORD, ILLINOIS.

KNITTING-MACHINE PATTERN MECHANISM.

996,059.

Specification of Letters Patent. Patented June 27, 1911.

Application filed September 5, 1908. Serial No. 451,813.

To all whom it may concern:

Be it known that I, WILSON WORTH BURSON, a citizen of the United States, residing in Rockford, in the county of Winnebago 5 and State of Illinois, have invented a new and useful Improvement in Knitting-Machine Pattern Mechanism, of which the following is a specification.

This invention relates to the pattern mechanism used in that class of knitting machines known as straight knitting machines, the same having two parallel rows of needles mounted on suitable frames, with an opening between them for the knit fabric to pass 15 through.

My object in the invention has been to provide improved mechanism whereby such cylinders may control the positioning of the needles.

20 The nature of my improvement will be fully understood from the description thereof given below, when considered in connection with the accompanying drawing forming a part of the description, and in which 25 drawing,

Figure 1 is a partial cross section of the machine showing the needle mechanism and a portion of the pattern cylinder. Fig. 2 is a similar view somewhat enlarged from 30 Fig. 1, showing the parts in a different position from that shown in Fig. 1. Fig. 3 is a partial plan of the cylinder. Fig. 4 is a detail view of one of the vibrating levers. Fig. 5 is an end elevation of a knitting machine embodying my present improvements. 35 Fig. 6 is a side view of the switch wheel controlling the rotary movements of the pattern cylinders.

In said drawing, 5 represents a portion of 40 the stationary frame of the machine, and 6, 7, 8 and 9 are portions of the stationary longitudinal bars or parts forming the needle beds and, in which the needles are supported at an angle to the horizontal as shown. The 45 needles are shown at 10, 10, those of opposite rows being adapted to be projected across each other when in action. The needles are supported in the beds upon what are known as bottom plates 11 arranged 50 edgewise immediately below them, and together with said bottom plates are confined between what are known in the art as wall plates 12. Above each needle is a filler plate 24, also arranged edgewise between the wall 55 plates, and preventing vertical movement of the needle. The wall plates are staid

in position by their entrance in transverse grooves formed in the needle bed in the manner usual in these machines. The needles are projected into acting position 60 and are withdrawn therefrom by jacks 13, the upper ends of which have notches adapted to engage the turned up lower ends of the needles, as plainly shown. The jacks upon their upper edges have lugs 14, which are 65 engaged by the cam devices on longitudinally moving cam bars 15, traveling in ways formed in the supporting bed and by such cam bars are actuated longitudinally so that they carry the needles into and out of acting 70 positions. The cam devices of the bars 15 are not shown, but their construction is well known to manufacturers of this class of knitting machines.

The pattern cylinder 16 is a cast cylinder 75 located stationarily and adapted to rotate, the operating parts of which are located at and near its end, and those parts of its periphery at which the needles should move into non-acting position are wholly cut away 80 giving the end of the cylinder a stepped formation so that the remaining parts of the cylinder are very light in weight as compared with previous constructions. The cylinder is adapted to act on the vibrating 85 levers 17 in such manner as to cause the lifting of the jacks so as to bring their lugs 14 into the path of the cam devices of bars 15, and also to lower the jacks so as to withdraw them from engagement with the cam 90 bars. The jacks are free to move longitudinally in said levers, so that the cams can slide the jacks upward or downward, and thus project the needles into acting position or withdraw them to normal position. The 95 levers 17 are supported at each side by the wall plates, and are pivoted at 18, so that they may rock and thereby be able to lift or depress the jacks. The pivot is located nearer one end of the lever than the other in 100 order that the latter may be the heavier so that when it has fallen to its lowermost position, its own gravity will effectually hold it against rising from that position, and also in order that the risers 21, described below, may be made short and still produce the necessary amount of movement at the long end of the levers, and allow the pivots of the levers to be located near the periphery of the cylinder. I do not, however, rely upon 110 either gravity or springs to give movement to the levers, but instead I provide means

whereby they may be positively operated at the proper times, and these means are described in the following paragraph.

The levers have each two downwardly projecting points or feet, one 19 located laterally of the body of the lever and at the initial or forward end of the same, and the other 20, under the body but at the opposite side of the pivot from foot 19. Both feet 10 are beveled at their forward and also at their back faces, so that the feet 19 will ride over the risers 21 mentioned below, whether the cylinder be moving forward or back, and so that the feet 20 after having passed off the 15 surface of the cylinder, as described below, will again be lifted up onto said surface whenever the same again presents itself in either the forward or back movement of the cylinder. The cylinder is provided with a 20 series of risers or buttons 21 so located that they pass under and lift the feet 19 of the levers a short distance above the cylinder surface as seen at Fig. 2, and this operation is coincident in the case of each lever 25 with the passing of the foot 20 of the same lever over the step 22, that being the point at which the cylinder is cut away so far as it controls the lever being described. The lifting of foot 19 and the stepping off of 30 foot 20 allows the lever to rock from the position of Fig. 1 to that of Fig. 2 and this results in depressing the jack so it cannot be acted on by the cam bar 15. In this position the lever rests upon the rod 23 which 35 passes transversely through the wall plates, and acts as a stop to limit the downward movement of the lever. The lever and jack continue in the position just described until the cylinder has moved far enough to bring 40 another acting portion of its surface under the lever. When this occurs the feet 19 and 20 will both slide up onto the surface of the cylinder and continue to ride thereon until the riser 21 and step 22 again appear or an- 45 other similar riser and step appear in their stead, and causes the rocking of the lever as above described. I show the lever with both feet on the solid part of the cylinder in Fig. 1, and in this position the lever is raised so 50 that it brings the jack into position for engagement with cam bar 15, and continues the needle in action until the riser and step cause the rocking of the controlling lever and the withdrawal of the jack.

55 The pivot 18 is located quite near the periphery of the pattern cylinder. In practice, this is desirable, and in this instance I have located it as near as the clearance required by the risers 21 would permit.

60 The pattern cylinders are rotatable in both directions, and lift the levers when moving back as well as when moving forward. The cylinders are supported on shafts 25 and they are provided with intermeshing gears 65 26 so that they move together at all times.

At 27 is a comparatively small gear meshing with one of the gears 26, and on the same shaft with gear 27 is a toothed wheel 28, the teeth of which engage the outstanding rib 29 of a wheel 30 mounted upon a cross shaft 31 70 continuously rotated by gears 32 and 33 from the power shaft 34 driven by the belt pulleys 35. The rib 29 embodies a switch section 36, and this section is adapted to be shifted in either direction from the central 75 or neutral position shown, or if shifted to either side it may be shifted back to the central position, and the means for accomplishing these changes of position are fully disclosed in my said application 408,902 and 80 governed by the wheel 40 driven by a ratchet 41 and the pawl 42 actuated by the cam 43 on the shaft 31. The arm 44 on shaft 45 carrying cam blocks 46 operating the arm 47 attached to the switch section 36 is a portion 85 of the switch operating means.

I claim:—

1. The combination with the needles, of the jacks, the reciprocating cam bars operating the needles, pivoted levers controlling 90 the jacks and provided with feet 19 and 20, a stationarily located pattern cylinder rotatable in both directions having at its end risers and the stepped formation for rocking the levers and means for rotating said 95 cylinder in both directions.

2. The combination in pattern mechanism for knitting machines, with the needles of the jacks, of the pivoted levers for raising and lowering the jacks, said levers having 100 feet 19 and 20, a stationarily located pattern cylinder rotatable in both directions having formed at its end risers and cut away steps for rocking the levers, and means for rotating the cylinder in both directions. 105

3. The combination in pattern mechanism for knitting machines, with the needles of the jacks, the pivoted levers for raising and lowering the jacks, said levers having feet 110 19 and 20, a stationarily located pattern cylinder rotatable in both directions having risers for lifting feet 19 and also having portions of its surface cut away in steps to allow the rocking of the levers and means for rotating the cylinder in both directions. 115

4. The combination in pattern mechanism for knitting machines, of a stationarily located pattern cylinder rotatable in both directions mutilated by cutting away from its end in steps those portions at which the pivoted jack controlling levers should be depressed, means for rotating the cylinder in both directions, and a series of such levers, riding upon and rocked by said cylinder. 120

5. The combination with a stationarily 125 located pattern cylinder rotatable in both directions having risers 21 and cut away portions 22, of pivoted jack controlling levers having feet 19 and 20 both of which are beveled on their front and their rear faces 130

so that they are adapted to be lifted by the cylinder when moving either backward or forward and means for rotating the cylinder in both directions.

- 5 6. The combination with a stationarily located pattern cylinder rotatable in both directions having non-acting portions of its periphery cut away, of pivoted jack controlling levers riding on the cylinder and falling 10 out of action at such cut away portions and

means for rotating the cylinder in both directions, such levers being provided with beveled faces whereby they may ride up and on to the surface of the cylinder after dropping off at the mutilations.
